[57] CLAIM

The ornamental design for a lead wire cutting machine, as shown and described.

DESCRIPTION

FIG. 1 is a top, front and left side perspective view of a lead wire cutting machine showing my new design;

FIG. 2 is a front elevational view;

FIG. 3 is a rear elevational view;

FIG. 4 is a left side elevational view;

FIG. 5 is a right side elevational view;

FIG. 6 is a top plan view;

FIG. 7 is a bottom plan view; and,

FIG. 8 is a top plan view thereof, shown in working condition.

FIGS. 2-8 have been drawn to a reduced scale with respect to FIG. 1.
